[57] CLAIM

The ornamental design for a merchandising package, as shown and described.

DESCRIPTION

FIG. 1 is a front elevational view of a merchandising package showing a first embodiment of my new design in an unfolded condition;

FIG. 2 is a left side elevational view thereof, the right side elevational view being a mirror image thereof;

FIG. 3 is a left side elevational view thereof in a folded condition, the right side elevational view being a mirror image thereof, the broken line showing of merchandising is for illustrative purpose only and forms no part of the claim;

FIG. 4 is a left side elevational view similar to FIG. 3 but with the broken line showing of the merchandise removed;

FIG. 5 is a top plan view of FIG. 1;

FIG. 6 is a bottom plan view of FIG. 1;

FIG. 7 is a front elevational view showing a second embodiment of my new design in an unfolded condition; and,

FIG. 8 is a left side elevational view of FIG. 7, the right side elevational view being a mirror image thereof.

The top, bottom and side views of the second embodiment (FIG. 4) are the same as that of the first embodiment as shown in FIGS. 5 and 6.
